SMOKER'S PIPE

Martin A. Gross, Fairborn, Ohio

Application June 19, 1951, Serial No. 15,604

Term of patent 3½ years

(Cl. D85—8)

To all whom it may concern:

Be it known that I, Martin A. Gross, a citizen of the United States of America, residing at Fairborn, county of Greene, State of Ohio, have invented a new, original, and ornamental Design for a Smoker's Pipe, of which the following is a specification, reference being had to the accompanying drawing, forming a part hereof:

In the drawing:

Fig. 1 is a plan view of a smoker's pipe, showing my new design;

Fig. 2 is a side elevational view;

Fig. 3 is a front elevational view; and

Fig. 4 is a front perspective view.

The dominant features of the design reside in the part drawn in full lines as shown.

I claim:

The ornamental design for a smoker's pipe, substantially as shown and described.

MARTIN A. GROSS.
